UNITED STATES PATENT OFFICE.

JOHN D. LOWRY, OF LOS ANGELES, CALIFORNIA.

ICE-CREAM-BRICK SLICER AND RECEPTACLE.

Application filed March 17, 1925. Serial No. 16,201.

To all whom it may concern:

Be it known that I, JOHN D. LOWRY, a citizen of the United States, and resident of Los Angeles, Los Angeles County, State of California, have invented new and useful Improvements in an Ice-Cream-Brick Slicer and Receptacle, of which the following is a specification.

This invention relates to apparatus for handling food products and more especially to means for slicing bricks, loaves or cakes of food substances.

More particularly, the invention relates to means for slicing brick-shaped bodies into slices of predetermined thickness, uniformly for the length of the block.

For example, it is the practice to serve ice-cream in the form of slabs cut transversely from a brick. Large quantities of these bricks are consumed in various places of refreshment and other establishments, and in homes. The slicing is done more or less indifferently with the result that no uniform number of slices is obtained per brick, when cutting up a series of bricks, though these may all be of the same size.

It is desirable to provide for the cutting of each brick (of a given size) into a uniform number of slices, especially in public service stands so that each customer will receive a like slice and satisfaction of service obtained.

Another object is to provide for accuracy of slicing with rapidity of operation, and to provide for cutting of one or a number of slices at one operation.

Another object is to provide a combined slicer and receptacle forming a practically complete box in which a sliced or unsliced brick may be kept in a cooling chamber or on a cold table, and to provide a receptacle having a closure part permitting ready access to the contents, for slicing and for removing a slice. Another object is to provide a combined receptacle and slicer of very simple parts and construction, to thus enable low cost of production and reasonable selling price. An object is to provide a combined gaging receptacle and cutting or slicing means in the form of cleavers each movable independently of the other and free from the receptacle closure but operable thereby as a gang for concurrently slicing an ice-cream brick (or other sliceable body in the receptacle) into a row of slices each sepa-

rated by a cleaver blade from the other to prevent congealing or running together while reposing in the receptacle.

Again, an object is to provide a food receptacle which is devoid of small pockets and has all parts freely open for thorough cleansing and thus achieving a perfectly sanitary condition of the utensil when scalded and rinsed out.

Numerous other objects and advantages will be made manifest in the following specification of apparatus of one embodiment of the invention as illustrated; it being understood that modifications, variations and adaptations may be resorted to within the spirit of the invention and its scope as is here claimed.

Figure 1 is a perspective of the receptacle, closed.

Figure 2 is a vertical cross-section, the closure being in open position.

Figure 3 is a perspective of one end portion of the receptacle.

Figure 4 is a front elevation of a portion of the receptacle, showing a latch keeper.

Figure 5 is a detail sectional view showing a blade gang-key for keying all the cleaver blades to the closure top to open therewith.

Figure 6 is a detail showing a form of bolt for latching the top to the receptacle, for carriage purposes.

In its preferred embodiment, the utensil includes a receptacle or tray portion having a flat bottom 2 of a width and length determined only by the dimensions of a brick of ice-cream or other object to be severed (the use extending to any material capable of being sliced by the cleaver blades of the device). Along the bottom extend parallel walls 3 which are serrated by vertical, equispaced kerfs 4 running to the bottom; opposite kerfs being aligned across the bottom, which has no end walls. The height of the walls is somewhat greater than the thickness, vertically, of a given brick of ice-cream, which is indicated by dash lines B.

Extending along a lower, outer corner of the receptacle is a pivot rod 5 hung in suitable bearings 6 and mounted on this rod is a series of parallel, upright blades 7 which, when tipped out to open position as in Fig. 2, lie clear of the space between the walls 3-3 so as to permit the ready insertion of a brick B, if such is to be sliced. The in-

ner, upright edges of the blades 7 are disposed in the near slots or kerfs 4 and thus sustained in their relation.

Preferably, there is provided at one end 5 a gage blade 8 tilttable, on rod 5, inwardly across the receptacle end to form a stop against which to thrust the end of the brick inserted for slicing. After the brick has been so disposed in the receptacle then the 10 outthrown blades 7 may, commencing with the one nearest the stop plate 8, be forced in and across the brick, to slice off one piece at a time, successively, if so desired. To help such slicing movement each cleaver 15 blade 7 may have a projecting finger grip 7^a on its corner most remote from the pivot rod 5. After the slice is severed the stop gage 8 is thrown back out of the way to provide access to the brick end.

20 This simple form of the device enables quick and accurate slicing as the blades are individually forced in, but to obtain a quicker action and simultaneous movements of the blades 7 I provide a universal frame including a top 10 corresponding to the bottom 2 and having rigid end panels 11 pivoted on the ends of the pivot rod 5 and being tilttable across the ends of the receptacle or tray part 2-3. Along the top 10 is a rigid corner flange 12 spaced back far enough to lie against the near corners of the blades 7 which, as shown in Fig. 1, project beyond the back wall 3 in order to receive the pivot rod 5. The blades 7 project up enough above the 25 walls 3 to be engaged by the top 10 or a part thereof or thereon, and be forced down through the brick B to the bottom 2 when the top structure is tilted up over the receptacle in which the brick has been placed 30 against the previously inwardly set gage plate 8.

Therefore, when desired, the whole brick can be cut into a number of slices, whose thickness will be determined by the spacing 45 of the slicing cleavers 7. Obviously, if alternate cleavers be detached from the pivot rod 5, a doubled thickness of slice will be cut, and so on by suitable spacing of the cleavers. When ice-cream sandwiches are 50 to be made, a rather thin slicing is utilized, say three-eighths inch thickness.

It may be desirable to withdraw all of the cleaver blades at one time by the opening movement of the closure so that the 55 slices can be rapidly, successively taken out or the whole, sliced brick may be removed. To that end a key-bar 14 is slidably mounted on the under face of the top 10 and has projections 15 extending up through slots 16 in 60 the top and which allow for just enough movement of the key-bar to shift key-lugs 17 into notch roots 18 provided in the top edges of the cleaver blades 7. When so interlocked to the key-bar the blades 7 will 65 be pulled up and outwardly on their pivot

rod 5 as the top is swung back to the open position. To release the blades the key-bar is shifted to retract the lugs 17 from the blades; the body of the key-bar swinging clear of the blades when the top is swung out.

70 The projections 15 provide for attachment of a foldable handle 20 above the top 10 if so desired, though it may be otherwise attached.

75 The utensil may be utilized as a closed container for storage in a cooling chamber, and to enable transportation by use of its handle 20 the top is adapted to be locked closed. This is accomplished by any suitable 80 means, as a sliding bolt 22 on one part to engage a keeper 23 on another part.

In Figs. 1 and 2, the cover part has a hinged flange 25 curved to conform with the outline of the blade finger grips 7^a. In 85 this case the bolt 22 is mounted on the flange 25 in a position to register with a keeper 23 on the near wall part 3.

The stop or gage plate 8 is not engaged by and does not move out with the key-bar, 90 but forms a retractive end wall for the brick.

What is claimed is:

1. An ice-cream brick slicer including parallel, vertically slotted side walls and a bottom forming an open ended tray, and a series of relatively independent and separately tilttable cleaver blades adapted to form partitions from wall to wall and extending substantially from the bottom of the tray to the top thereof, for completely separating the severed slices and preventing them from merging together after the cut is made.

100 2. An ice-cream brick slicer including an open top tray part having plane side walls with recesses from top to bottom and being open at its end, and a gang of independently movable pivoted cleaver blades mounted along one side of the tray to be moved into transverse position and lie in aligned recesses in the walls.

110 3. An ice-cream brick slicer including a tray part having recessed side walls and being open at one end and at the top, a stop plate adjustable across the open end to position an inserted brick, and tilttable cleaver blades movable into slicing position across the tray; the stop plate being pivotally mounted at one lower corner so as to swing to and from a closed position at one end of the tray.

120 4. An ice-cream brick slicer including a tray part having recessed side walls and an open end, a plate at the open end, a gang of independently movable slicing blades, and means for concurrently moving all of the blades into slicing position across the tray.

125 5. An ice-cream brick slicer including a tray part, a gang of independently movable

- slicing blades, and means for concurrently moving all of the blades into slicing position across the tray and being retractive independently of the thrown cleaving 45 blades to leave them for subsequent withdrawal from the brick.
- 5 6. In a slicing device, a tray part having opposite slotted walls and an open end, a tiltable stop plate adjustable in the open 10 end, a gang of cleaving blades, and means for swinging the blades across and into the tray and for retracting the blades.
- 10 7. In a slicing device, a tray part having opposite recessed walls and an open end, a 15 swinging stop at the open end, a gang of cleaving blades, and means for swinging the blades into cutting position across the tray and for retracting them and including a releasing device to leave the blades in separating position between the slices of the substance cut.
- 20 8. In a slicing device a tray part open at each end and having slotted side walls, and a gang of slicing blades mounted in parallel relation and each being separately tiltable into and out of the tray, and means for moving the blades.
- 25 9. In a slicing device, an open top tray part having side walls and an open end, and a gang of pivoted slicing blades tiltably movable through slots in one of said side walls and being maintained in parallelism thereby in open and closed positions.
- 30 10. In a slicing device, a tray part having 35 side walls, a pivot rod extending along a lower corner of the tray, and a gang of slicing blades each independently pivoted on the rod and being independently movable as to each other.
- 35 11. A combined receptacle and ice-cream 40 brick slicer including a walled tray part, a closure having a top for the tray part and being pivotally attached thereto along a lower corner thereof, and cleaving means
- similarly pivoted on the tray and movable from inner transverse position across the tray to a retracted position in the opened closure.
- 45 12. A combined receptacle and ice-cream brick slicer including a walled tray part, 50 a closure having a top for the tray part and being pivotally attached thereto along a lower corner thereof, and cleaving means similarly pivoted on the tray and movable from inner transverse position across the tray to a retracted position in the opened closure; said closure having a portion to engage and swing the cleaving means into the tray to slice a brick therein.
- 55 13. A combined receptacle and ice-cream slicer including a walled tray part, a closure having a top for the tray and being pivotally attached thereto, cleaving means pivoted on the tray for movement into transverse position therein, and means for securing the closure and the cleaving means for concurrent outward movement after a brick 60 has been sliced.
- 65 14. A combined receptacle and ice-cream brick slicer including a walled tray part, a closure having a top for the tray and being pivotally attached thereto, and cleaving means pivotally attached to the tray for transverse movement thereinto; said cleaving means including flat blades, and a key-bar means to interlock the blades and said closure for concurrent outward movement 70 from the tray.
- 75 15. A combined receptacle and ice-cream brick slicer including a walled tray part, a closure having a top for the tray and being pivotally attached thereto, cleaving means pivotally attached to the tray for transverse movement thereinto, and means for latching the tray part and the closure in closed relation; whereby enabling carriage by a handle 80 on the closure.

JOHN D. LOWRY.
